UNITED STATES PATENT OFFICE.

ANDREW V. RYDER, OF SCIO, OHIO.

WHEELED CULTIVATOR.

SPECIFICATION forming part of Letters Patent No. 633,160, dated September 19, 1899.

Application filed October 26, 1897. - Serial No. 656,429. (No model.)

To all whom it may concern:

Be it known that I, ANDREW V. RYDER, a citizen of the United States, residing at Scio, in the county of Harrison and State of Ohio, 5 have invented certain new and useful Improvements in Wheeled Cultivators, of which the following is a specification, reference being had therein to the accompanying drawings.

10 This invention relates to certain new and useful improvements in wheeled cultivators.

One of the objects of my invention is to provide means for throwing the weight of the frame forward of the wheel-spindles in order 15 to keep the cultivator properly balanced when the cultivator-beams are raised from the ground to keep the pole from tipping up and lifting against the horses' necks.

Other objects of the invention are to improve 20 the construction of cultivators in the respects hereinafter pointed out and particularly set forth in the claims.

My invention also has reference to details of construction and arrangement hereinafter 25 appearing and particularly pointed out in the claims.

In the accompanying drawings, on which like reference-letters indicate corresponding parts, Figure 1 is a plan view of a cultivator 30 embodying my improvements; Fig. 2, a side elevation of the same with one of the wheels removed, showing the cultivator-beams in cultivating position; Fig. 3, a similar view to Fig. 2, showing the cultivator-beams in their raised or up position and wholly out of contact with the ground; Fig. 4, a detail perspective view of one of the adjustable arched axle-supports and showing the means for holding the axle within said support and a portion 35 of the connecting-bar for connecting the supports, and Fig. 5 a detail view of the compensating mechanism and diagram showing its operation.

In illustrating my improvements I have 40 shown them connected to an old form of cultivator, in which the letter A represents a suitable frame and the letter B a pole attached thereto. This frame is supported by arched axles C, having spindles D, upon which 45 are fitted wheels E in the usual manner. Ordinary cultivator-beams, as shown at F, are pivoted to a bar G, which bar is adjustable up and down in the frame structure, whereby 50 the cultivator-shovels H, carried by the cul-

tivator-beams, may be adjusted to run deeper 55 or shallower, as desired.

Near the rear end of the cultivator-beams is pivotally attached a standard I by means of a bolt J passing through the standard and cultivator beam. To the upper end of this 60 standard is secured a band or casting K, hinged to a suspension-arm L, having branches at its lower end, as seen at M, which branches are rigidly secured in any suitable manner to a rock-arm N, carried in brackets O, extending 65 from a sleeve P.

To the rock-arm at Q is attached what I term my "compensating" mechanism. This consists of a bar S, at one end of which is attached a chain T, preferably a sprocket-chain, 70 which passes around a sprocket-wheel U, carried by a bracket V, secured to the frame of the machine, and has its other end attached to a spring W and which is also connected to the bar S. The spring W may be tightened 75 or loosened, according to which hole its links W' are engaged with. It will be observed that the sprocket-wheel U is so mounted that it turns in an eccentric path when partially rotated, as it will be by the tension of the 80 spring when the bar S moves from the full-line position to the dotted position shown in Fig. 5, as is the case when the cultivator-beams are raised from the ground. Thus this eccentric lifting sprocket-wheel is in effect an 85 eccentric take-up for the spring. Thus all slack in the chain due to such movement of the bar S is taken up by the eccentric take-up and the tension remains nearly uniform, which is a valuable feature in cultivator-beam-operating mechanism. When the cultivator-beams are in their lowered position and the plows are cultivating the soil, the raising effect of the spring W is *nil* or neutral, as the pull is directly through the dead-center, so to speak—that is, the pivotal point 90 of the eccentric take-up, the point Q where the bar S connects with the rock-arm N, and the pivotal point of said rock-arm are all in line when the shovels are in the ground, and the pull being along the line connecting these three points no effect is produced on the cultivator-beams. The instant, however, the operator raises the cultivator-beams by taking hold of the handles at the point Q is raised 95 above the line of pull and the spring is at once effective.

Near the upper end of the suspension-arm L,

I have placed a sheave or pulley Y, over which passes a suitable lifting-chain Z and secured to the standard I by hooking over any one of the teeth *a*, carried by the standard. The 5 other end of this chain is attached to a spring Z', which in turn is attached to a rock-arm *b*, secured to a rock-shaft *c* by means of a set-screw *d* or otherwise, as desired. This spring assists in raising the cultivator-beams. To 10 the other end of the rock-arm *b* is attached a rod or bar *e*, which connects with the castings *f*, secured to the wheel-spindles, but which allow the wheel-spindles D to be partially rotated. This is done by means of a suitable 15 lever mechanism attached to the rock-shaft *c* and which consists of a lever P', a detent P" carried thereby, and a toothed-segment P"', with which said detent engages. When the detent is released from engagement with the 20 toothed segment, the lever may be thrown forward or backward, by which operation the rock-shaft is partially rotated and the lower end of the rock-arm thrown backward or forward, as desired, and through the rod *e* throws 25 the wheel-spindles back of the bearing-boxes P, presently to be described, in order to bring the weight of the frame forward of the wheel-spindles when the cultivator-beams are in their raised position or out of the ground, as 30 shown in Fig. 3. This more equally balances the cultivator when out of cultivating position and prevents the pole from lifting up on the horses' necks. The upper end of the rock-arm *b* when the beam is raised is thrown forward and takes up any slack on the chain Z, and hence the action of the spring Z' is not 35 lessened when the beams are raised.

Referring now to the means for spreading the wheels apart more or less and at the same 40 time allowing the arched axles to partially rotate, it will be seen that I provide a suitable bearing-box P, into which the upper portion *j* of the arched axle is slipped. In this bearing-box a slot or pocket *j'* is formed, into 45 which a ring or collar *k*, provided with a suitable set-screw *l*, is placed. The axle is slipped through this collar *k*, and when in the desired position the set-screw is tightened upon it and prevents its withdrawal from the collar, 50 which comes in contact with the shoulders forming the sides of the slot or pocket *j'* and holds the axle within the bearing. When it is desired to spread the wheels, the set-screws *l* are loosened and the axle is shifted or slid 55 outward or inward to the desired position, when the set-screw is then tightened and the axle is held in such adjusted position. Two of these bearings are used in the cultivator illustrated, one for each arched axle, and are 60 secured to the frame structure by means of bolts *m* and *n*.

Having thus fully described my invention, what I claim as new, and desire to secure by Letters Patent, is—

65 1. In a wheeled cultivator, a suitable frame,

wheel-spindles connected therewith, a cultivator-beam pivotally connected to the frame, and means acting to both lift the beam and change the position of the frame relative to said wheel-spindles whereby the weight of the frame is thrown forward of the spindles when the beam is up. 70

2. In a wheeled cultivator, the combination with a suitable frame, having wheel-spindles connected therewith, and a cultivator-beam, 75 of a rock-shaft carried by said frame, means connecting said beam and rock-shaft, and means for operating said rock-shaft to lift the beam and change the position of the frame relatively to the wheel-spindles, whereby the 80 principal weight of the frame is thrown forward of the wheel-spindles, substantially as shown and described.

3. In a wheeled cultivator, the combination with a suitable frame having wheel-spindles 85 connected therewith, and a cultivator-beam, of a rock-shaft carried by said frame, means connecting said rock-shaft and beam, a rock-arm carried by said shaft, a connecting-rod connecting one of said wheel-spindles with 90 said rock-arm, and means for operating said rock-arm, whereby the relative position of said frame and said wheel-spindles will be changed and the beam lifted, substantially as shown and described. 95

4. In a wheeled cultivator, the combination with a suitable frame having wheel-spindles connected therewith, and a cultivator-beam, of a rock-shaft carried by said frame, a lever 100 engaging with said shaft and adapted to rock the same, and suitable mechanism for connecting said rock-shaft and one of the wheel-spindles and cultivator-beam, whereby when the rock-shaft is operated by said lever, the position of the wheel-spindles will be changed 105 and the beam lifted.

5. In a wheeled cultivator, the combination of a frame, a cultivator-beam pivotally supported near the forward end of said frame, a suspension-bar pivotally mounted on the 110 frame near the rear thereof, a connection between said suspension-bar and said cultivator-beam, a compensating yielding lifting mechanism between said suspension-bar and the frame, wheels for the cultivator, a bent 115 axle for the wheels hinged to said frame, a rock-shaft, a lever for operating the same, a connection between an arm on said shaft and said bent axle, and a flexible connection between an arm on said rock-shaft and said connection between the suspension-arm and the beam and slidably supported by said suspension-arm, substantially as described. 120

In testimony whereof I affix my signature in presence of two witnesses.

ANDREW V. RYDER.
